Primary Examiner — Robin V Webster(74) *Attorney, Agent, or Firm* — Paul D. Bianco; Lourdes Perez; Fleit Gibbons Gutman Bongini & Bianco PL(57) **CLAIM**

The ornamental design for a paint spray gun rear portion, as shown and described.

DESCRIPTION

FIG. 1 is a first perspective view of a paint spray gun rear portion according to the present invention;

FIG. 2 is a second perspective view of the paint spray gun rear portion of FIG. 1;

FIG. 3 is a first side view of the paint spray gun rear portion of FIG. 1;

FIG. 4 is a second side view of the paint spray gun rear portion of FIG. 1;

FIG. 5 is a back view of the paint spray gun rear portion of FIG. 1;

FIG. 6 is a top view of the paint spray gun rear portion of FIG. 1; and,

FIG. 7 is a bottom view of the paint spray gun rear portion of FIG. 1.

The front view of the paint spray gun does not contain any ornamental features which are claimed. Accordingly, a front view of the paint spray gun rear portion is not shown.

The broken lines are for illustrative purposes and form no part of the claimed design.
